United States Patent Office

Des. 183,890
Patented Nov. 11, 1958

183,890

OUTDOOR FIREPLACE

Helen J. Kulikowski, Fort Lee, N. J.

Application November 27, 1957, Serial No. 48,696

Term of patent 14 years

(Cl. D81—10)

The figure is a perspective view of an outdoor fireplace, showing my design.

The side and end of the fireplace not visible in the drawing have the same appearance as the side and end shown.

I claim:

The ornamental design for an outdoor fireplace, as shown and described.
